METHOD OF AND APPARATUS FOR
BRAIDINGBrooke W. Lerch, Baltimore, Md., assignor to
Western Electric Company, Incorporated, New
York, N. Y., a corporation of New York

Application October 9, 1947, Serial No. 778,773

6 Claims. (Cl. 87—6)

1

This invention relates to methods of and apparatus for braiding, and has for an object thereof the provision of new and improved methods of and apparatus for braiding.

A method illustrating certain features of the invention may include braiding metallic strands over an elongated article, and overforming the strands on the article so that the strands are substantially unstrained in their braided positions.

An apparatus illustrating certain features of the invention, and by means of which methods embodying features of the invention may be practiced, includes means for advancing an elongated article along a predetermined path, means for braiding a plurality of strands, at least some of which are metallic, into a covering around an elongated article so advanced, and means for twisting the covered core through a predetermined angle about the longitudinal axis thereof in such a direction that the metallic strands tend to be wound more closely upon the core, whereby the metallic strands are overformed on the core and cling closely to the core.

A complete understanding of the invention may be obtained from the following detailed description of a method and apparatus forming specific embodiments thereof, when read in conjunction with the appended drawing, in which:

Fig. 1 is a fragmentary, elevational view of an apparatus illustrating certain features of the invention;

Fig. 2 is an enlarged, horizontal section taken along line 2—2 of Fig. 1, and

Fig. 3 is an enlarged, fragmentary elevation taken along line 3—3 of Fig. 2.

Referring now in detail to the drawing, a generally elliptical core 10 (Fig. 2) which includes conductors 11—11 enclosed in an insulating covering 12 generally elliptical in shape is advanced through a braider 14 of a well known type. The braider 14 rotates bands of steel wires 16—16 in one direction around the core 10, rotates bands of cotton strands 18—18 around the core in the opposite direction, and interweaves the bands of steel wires with the bands of cotton strands into a braided covering 20. Hence, the steel wires 16—16 are all wound around the core 10 in a single direction.

The core 10 with the braided covering 20 thereover is advanced through a generally elliptical opening 22 in a die 24, which holds the portions of the core 10 and the braided covering 20 passing through the opening 22 in predetermined positions. The core 10 and the braided covering

20 then are advanced through a generally elliptical opening 26 in a die 28, which is spaced slightly above the die 24, as viewed in Fig. 1. The opening 26 is complementary in cross section to the cross section of the core 10 and the braided covering thereover, and the major axis of the opening 26 is at a substantial angle with respect to the major axis of the opening 22 in the die 24. Hence, the portion of the core 10 and the covering 20 between the die 24 and the die 28 is twisted through this angle. This twisting tends to wind the steel wires 16—16 more tightly upon the core 10, which action is permitted by the resilient covering 12, so that, when the wires spring from their residual resiliency back to positions in the untwisted portion of the covered core above the twisted portion thereof, as viewed in Fig. 3, the wires are substantially unstressed.

Operation

In the operation of the apparatus described hereinabove to accomplish one method embodying the invention, the core 10 (Fig. 1) is advanced upwardly through the braider 14 which interbraids the steel wires 16—16 with the cotton strands 18—18 to form the braided covering 20, and as the wires 16—16 are applied to the core 10 in a clockwise direction, as viewed in Fig. 2, they are tensioned to apply them quite closely to the core 10. As the braided covering 20 is advanced through the dies 24 and 28, the dies twist the core and the braided covering through the angle by which they are displaced to wind temporarily the steel wires 16—16 more tightly around the core 10 and to embed them partially and temporarily in the covering 12 as they are so wound. This temporary winding bends the wires 16—16 sufficiently beyond their elastic limits to cause them to stay close to the insulating covering 12 when the core 10 and the covering 20 untwist as they pass out of the die 28. As a result, the braided covering 20 does not unravel, and fits closely on the core even if the ends of the covering are not tied down.

The above-described method and apparatus serve to form tightly braided coverings from metallic and cotton strands upon cords. The above-described apparatus is simple in construction and inexpensive in its operation. The steel wires 16—16 need not be highly tensioned as they are braided upon the core 10 so that a light braider may be used and damage to the insulating covering 12 of the core 10 is prevented.

What is claimed is:

55 1. The method of braiding coverings upon

cores, which comprises advancing a core in a predetermined direction along a predetermined path rotating a plurality of non-metallic strands in a predetermined direction around said core, rotating a plurality of metallic strands around the core in a direction opposite to that in which the non-metallic strands are rotated, interbraiding the metallic strands with the non-metallic strands to form a braided covering over the core, and twisting the core and the covering in such a direction as to wind the metallic strands more tightly around the core so that the metallic strands tend to cling to the core.

2. An apparatus for braiding coverings upon cores, which comprises means for advancing a generally elliptical core along a predetermined path, rotating a plurality of metallic strands around the core at a predetermined point along said path in a predetermined direction, means for rotating a plurality of non-metallic strands around the core at said point in the direction opposite to that in which the metallic strands are rotated, interbraiding the metallic strands with the non-metallic strands to form a braided covering upon the core, a generally elliptical die positioned at a second point along the path through which the covering and the core pass for holding the portion of the covering and the core passing therethrough against rotation about the longitudinal axis of the core, and a second generally elliptical die spaced from the first generally elliptical die and held in a position in which the major axes of said dies form a substantial angle therebetween for causing the portion of the covered core between said dies to be twisted through said angle, whereby the portions of the metallic strands upon the portion of the core between said dies are temporarily wound more tightly upon the core.

3. The method of forming coverings upon cores, which comprises applying metallic strands around a core in a predetermined direction with a predetermined lay, advancing the core and the strands along a predetermined path, holding the core and the strands against rotation about the axis of the core at a predetermined point in the path, and holding the core and the strands at a point in the path spaced from the first-mentioned point in positions in which the portions of the core and the strands between said points are twisted in such a direction as to wind the strands upon the core more tightly so that the strands are overformed upon the core and lay closely thereon.

4. The method of forming coverings upon core including soft elastic exterior portions, which comprises advancing such a core along a predetermined path, serving closely a plurality of metallic strands around the core in a predetermined direction at a predetermined lay, holding the portions of the strands and the core at

one point in said path against revolution about the longitudinal axis of the core, guiding the portions of the strands and the core from said point in a twisted direction such as to wind the strands more tightly upon the core for a short predetermined distance from said point, and advancing the strands and the core from the last-mentioned point in the path in a non-twisted condition.

5. An apparatus for covering cores, which comprises means for advancing an eccentric core having an elastic outer portion continuously in a predetermined direction along a predetermined path, means for serving a plurality of metallic strands around an eccentric core advanced along said path, an eccentric guide positioned at one point in said path for holding the portions of the strands and the core passing through said point in predetermined positions, and a second eccentric guide spaced from the first-mentioned guide for guiding the portions of the core and the strands between the first-mentioned guide and the second-mentioned guide through a twisted path, whereby the strands are temporarily wound more closely upon the core so that the strands are overformed and are layed closely on the core.

6. An apparatus for covering cores, which comprises means for advancing a generally elliptical core along a predetermined path, serving a plurality of metallic strands around the core at a predetermined point in the path in a predetermined direction, a generally elliptical die positioned at a second point in the path through which the strands and the core pass for holding the portions of the strands and the core passing therethrough against rotation about the longitudinal axis of the core, and a second generally elliptical die spaced from the first generally elliptical die and held in a position which the major axes of the dies form a substantial angle therebetween for causing the portion of the covered core being advanced from one die to the other die to be twisted through said angle in such a direction that the portions of the metallic strands upon that portion of the core are temporarily wound more tightly upon the core.
